Primary Examiner—David G Muller

(74) Attorney, Agent, or Firm—Levine Bagade Han LLP

(57) **CLAIM**

The ornamental design for a heater cover, as shown and described.

DESCRIPTION

FIG. 1 is a top perspective view of the heater cover, showing my new design;

FIG. 2 is a right side elevation view of the heater cover shown in FIG. 1, the left side elevation view being a mirror image thereof;

FIG. 3 is a top plan view of the heater cover shown in FIG. 1; FIG. 4 is a bottom plan view of the heater cover shown in FIG. 1;

FIG. 5 is a top perspective view of the heater cover of FIG. 1 with an environment structure shown in broken lines;

FIG. 6 is a top plan view of the heater cover shown in FIG. 5; and,

FIG. 7 is a bottom plan view of the heater cover shown in FIG. 5.

All features illustrated in broken line are expressly disclaimed and form no part of the claimed design.

1 Claim, 5 Drawing Sheets
